ILLUMINATING DEVICE FOR POCKETBOOKS

Otto Hallbauer, Grantwood, N. J.

Application July 11, 1939, Serial No. 283,743

2 Claims. (Cl. 240—6.45)

This invention relates to improvements in pocketbooks and has particular reference to an illuminating device therefor.

An object of the invention is to provide an improved illuminating device of simple and practical construction which may be readily mounted on a closure member of a pocketbook and so arranged with respect to an opening in said member that the rays of light from the device will be directed outwardly through said opening when said closure member is closed and will also illuminate the interior of the pocketbook when the said member is opened.

The above and other objects will appear more clearly from the following detailed description when taken in connection with the accompanying drawings which illustrate preferred embodiments of the inventive idea.

In the drawings:

Figure 1 is a perspective view of a foldable pocketbook showing the illuminating device of the present invention mounted upon the closure flap of the pocketbook, with said member in closed position.

Figure 2 is a similar view, with the closure member in opened position.

Figure 3 is an end elevation partly broken away and shown in section.

Figure 4 is a section on the line 4—4 of Figure 2.

Figure 5 is a perspective view of a frame type of pocketbook showing the invention applied thereto.

Figure 6 is an end elevation of the pocketbook of Figure 5, partly broken away and shown in section, and

Figure 7 is a section on the line 7—7 of Figure 5.

Referring more particularly to Figures 1 to 4 of the drawings, the numeral 10 indicates the body of a pocketbook which includes a closure member or a flap 11. The interior of the pocketbook is provided with a lining 12 and at a convenient point, preferably adjacent the folding portion of the flap 11, the latter and said lining are provided with an opening 13 through which the rays of light from an incandescent lamp 14 may pass outwardly either when the closure flap 11 is in its closed or opened position, said lamp 14 being preferably mounted upon the interior surface of the flap 11 in juxtaposition to the opening 13. The mounting for the lamp 14 comprises a rectangular plate 15 secured to the outer surface of the flap 11 and provided with an elongated opening 16 which registers with the opening 13

in the flap. This plate 15 is secured to the closure flap by means of the screws 17 which extend through the plate and said flap 11 and into a pair of socket members 18 and 19 which constitute a support for the lamp 14. The socket member 18 is provided therein with a recess 20 adapted to receive one terminal of the lamp 14 and within said recess there is disposed a spring pressed plunger 21 urged outwardly by its spring to engage the adjacent end of the lamp so as to form an electrical conductor therefor through which the current for illuminating the lamp passes. Said lamp 14 is surrounded by a tubular glass inclosure 22 the ends of which bear against the socket members 18, 19 so as to be retained 23 in position thereby.

Within the socket member 19 there is disposed an insulated sleeve 23 which surrounds an electrical contact member 24 the rear end of which is spaced from the adjacent terminal of the lamp 14. A switch including a contact 25 is slidably mounted within the socket member 19, with said contact disposed within the member 24 for movement toward and away from the adjacent terminal of the lamp to make and break the electrical connection therewith. A small stud 26 on the member 25 is engageable in recesses 27 formed on the inner wall of the member 24 so as to frictionally retain the contact 25 in its operative and inoperative positions. A handle or switch arm 28 for the switch has its inner end connected to the member 25 and projects through an elongated recess 29 formed in the insulated sleeve 23 and socket member 19, and the head 30 of said handle is arranged exteriorly of said socket member so that the contact 25 may be adjusted.

A suitable source of current such as a small dry cell 31 is conveniently positioned in the body of the pocketbook at the bottom thereof between the lining 12 and the outer wall of the pocketbook, and conductors 32 and 33 leading from said battery 31 are connected, respectively, to the terminal member 24 and the socket member 19 so that when the contact member 25 is in engagement with the adjacent end of the lamp 14, the current in the conductor 32 will pass through the member 24 and terminal 25, and from thence through the lamp 14, the socket member 18, and back to the conductor 33 through the mounting plate 15, the screws 17 acting as conductors in this circuit.

With the lamp 14 mounted upon the interior surface of the flap 11, it will be apparent that the rays of light from said lamp will pass outwardly 35

through the openings 13 and 16 whether the flap 11 is opened or closed, and that when said flap 11 is opened as in Figure 2, the rays of light from said lamp will illuminate the interior of the pocketbook.

The invention is shown in Figures 5 to 7 in its adaptation to a frame type of pocketbook including a body portion having the closure member 34 provided with a lining 35 and having an opening 10 36 therein similar to the opening 13. The apertured mounting plate 37 is secured to the closure 34 by means of screws 38 which also secure the socket members 39 and 40 to the interior surface of the closure member 34. The lamp 41 is removably held within said socket members with one end of the lamp being engaged by the spring pressed plunger 42 disposed within the socket member 39. An insulated sleeve 43 is mounted in the socket member 40 and surrounds the terminal 20 44 within which is slidably mounted the contact 45 adapted for adjustment into and out of engagement with the adjacent terminal of the lamp 41, said contact 45 being frictionally maintained in its adjusted positions by means of a stud 46 engageable in recesses 47 in the terminal 44. Said contact 45 is provided with a handle or arm 49 which extends through an elongated slot 50 with the head 51 of said handle slidably engaged with the mounting plate 37 so that the switch may be 25 manipulated from the interior arrangement of said switch in the first modification herein described. Conductors 52 and 53 are connected, respectively, to the terminal 44 and socket member 40 and obtain their current supply from a dry cell battery 54 disposed at the bottom of the pocketbook between the outer wall thereof and the lining 35 thereby to establish an obvious circuit for the lamp 41 through the switching arrangement described. In this modification it will 30 be obvious that the rays of light from the lamp 41 will pass outwardly through the opening 36 whether the pocketbook be closed or opened, and that said rays will also illuminate the interior of the pocketbook when the latter is opened as in 35 Figure 6.

What is claimed is:

1. An illuminating device for pocketbooks comprising, in combination, a closure for a pocketbook having an opening therethrough, a mounting plate secured to said closure and having an 5 aperture registering with said opening, a lamp support including socket members secured to the interior of said closure adjacent said opening, fastening means for securing said plate and socket members to said closure, an electrical contact disposed within one of said socket members, an insulating sleeve surrounding said contact member to insulate it from said socket member, a lamp supported by said socket members in juxtaposition to said opening, a switch slidably mounted 10 within and engaging said electrical contact for movement into and out of engagement with said lamp and having a handle projecting through and slidably in said mounting plate, and an electrical circuit for said lamp including said socket 15 member, contact and said fastening means.

2. An illuminating device for pocketbooks comprising, in combination, a closure for a pocketbook having an opening therethrough, a mounting plate secured to said closure and having an 20 aperture registering with said opening, a lamp support including socket members secured to the interior of said closure adjacent said opening, fastening means for securing said plate and socket members to said closure, an electrical contact disposed within one of said socket members, an insulating sleeve surrounding said contact member to insulate it from said socket member, a lamp supported by said socket members in juxtaposition to said opening, a switch slidably mounted 25 within and engaging said electrical contact for movement into and out of engagement with said lamp and having a handle projecting through and slidably in said mounting plate, said switch and contact having interengaging means 30 for releasably retaining the switch in different positions of adjustment, and an electrical circuit for said lamp including said socket member, contact and said fastening means.

OTTO HALLBAUER. 45
